UNITED STATES PATENT OFFICE.

REUBEN B. BENJAMIN, OF CHICAGO, ILLINOIS, ASSIGNOR TO BENJAMIN ELECTRICAL MANUFACTURING COMPANY, OF CHICAGO, ILLINOIS, A CORPORATION OF ILLINOIS.

ELECTRICAL CONNECTER DEVICE.

Continuation of application Serial No. 823,234, filed March 7, 1914. This application filed August 11, 1917. Serial No. 185,782.

To all whom it may concern:

Be it known that I, REUBEN B. BENJAMIN, a citizen of the United States, residing at Chicago, in the county of Cook and State of Illinois, have invented new and useful Improvements in Electrical Connecter Devices, of which the following is a full, clear, concise, and exact description, reference being had to the accompanying drawing, forming a part of this specification.

My invention relates to electrical connector devices.

One of the objects of my invention is to provide improved means whereby receptacle devices of different types may be interchangeably secured to the same wiring base. Further objects will appear from the detailed description to follow and from the appended claims.

20 In the drawings illustrative of my invention—

Figure 1 is a side elevation of a receptacle and quick-detachable connector device;

Fig. 2 is an axial section of the receptacle shown in Fig. 1;

Fig. 3 is an axial section on the line 3—3 of Fig. 1;

Fig. 4 is a plan view of the lower portion of the receptacle;

30 Fig. 5 is a section on the line 5—5 of Fig. 3 looking in the direction of the arrow;

Fig. 6 is a fragmentary sectional view showing a cord-extension device connected with the wiring base shown in Fig. 3;

35 Fig. 7 is a plan view of the cord-extension cap of Fig. 6;

Fig. 8 is an axial section showing a different type of wiring base and receptacle;

Fig. 9 is a section on the line 9—9 of Fig. 8;

Fig. 10 is a section on the line 10—10 of Fig. 8;

Fig. 11 is a section on the line 11—11 of Fig. 9; and

45 Fig. 12 is a section on the line 12—12 of Fig. 10.

Referring now to the drawings in detail, and first to Figs. 1 to 5, inclusive, the construction here shown comprises a wiring base 15, a quick-detachable receptacle member 16, and a quick-detachable cap 17 which may be a cap such as used in a separable attachment plug for quick-detachable engagement with the receptacle portion 16.

The wiring base 15 comprises an insulating member 18 having a pair of binding-terminals 19 secured thereto. The insulating member 18 is housed and secured to an internally-threaded bushing 20 by means of a sheet-metal cap 21. The cap 21 may be secured to the insulating member 18 by means of an annular inwardly-extending bead 22 on the cap 21, which engages a corresponding annular groove in the insulating member 18. The cap 21 may be held from rotation with respect to the insulating member 18 by means of indentations 23 on the cap which engage corresponding depressions in the insulating member. The cap 21 may be secured to the bushing 20 by means of a tubular neck portion 24 on the bushing 20, which extends through and engages a corresponding portion 25 on the cap 21. Engaging parts of the neck portions 24 and 25 are slotted to form prongs 75 which are bent outwardly, thereby preventing relative rotation between the neck portions 24 and 25.

Each binding-terminal 19 comprises a binding-screw 26 (Fig. 5) the head of which is located in a recess 27 in the lower face of the insulating member 18, and a plate 28 (Figs. 3 and 5) into which the binding-screw 26 is threaded, located in a recess 29 in the upper face of the insulating member 18. The plate 28 may be held in place and insulated by means of a sealing insulating compound 30, which may be melted and poured into the recess 29, where it cools and hardens.

The receptacle member or portion 16 comprises an insulating member 31 and a pair of quick-detachable contacts 32 supported thereby for engagement with the contact-blades 33 of the cap 17. Each contact 32 is electrically connected with one of the conductor plates 28 by means of a conductor-strip 34 which engages the base portion 35 of the contacts 32 (Fig. 2), a tubular metal eyelet 36 which secures the strip 34 to the insulating member 31 (Fig. 3), and a screw 37 which extends through the eyelet 36 and through an opening in the insulating member 18 and is threaded into the conductor plate 28. These screws 37 also serve to mechanically connect the insulating member 31 to the insulating member 18.

The contacts 32 are held in place on the

insulating member 31 and in electrical contact with the strip 34 by means of a screw 38 (Figs. 1 and 2), threaded into a metal clamping member 39 which bears down on the strip 34 and base portion 35 to hold the contacts 32 firmly in place and to hold the portions 34 and 35 in good electrical connection. A strip of insulation 40 is interposed between the clamping member 39 and the strip 34 to prevent short-circuiting.

In wiring the device the internally-threaded bushing 20 is screwed on the end of a screw-threaded nipple, or the like, the insulating member 31 being detached from the insulating member 18. The feed-wires 41 are then secured underneath the heads of the screws 26 (Fig. 5). The insulating member 31 with its associated parts is then secured in place with respect to the insulating member 18 by threading the screw 37 into the conducting plate 28. The screw 37 is prevented from falling out of the eyelet 36 by means of friction washers 42 (Fig. 3) of fiber or other suitable material, the edges of the openings of which engage the screw 37 tightly enough to prevent the screw from falling out.

The circuit is from one of the feed-wires 41 through one of the binding-screws 26, one of the conductor-plates 28, one of the screws 37, one of the eyelets 36, one of the conductor-strips 34, one of the contacts 32, one of the contacts 33, through the translating device to the other contact 33, contact 32, conductor-strip 34, eyelet 36, screw 37, conductor plate 28, and binding-screw 26 to the other feed-wire 41.

In Figs. 6 and 7 I have shown a cord-extension cap substituted for the receptacle device 16; the insulating member 18, the cap 21, the binding-terminals 19, and the screws 37 are the same as in Figs. 1 to 5 inclusive.

The cord-extension comprises an insulating member 43 and a pair of binding-terminals 44 supported thereby. Each binding-terminal 44 comprises a binding-plate 45 secured to the insulating member 43 by means of an eyelet 46, and a binding-screw 47 threaded into the binding-plate 45. The binding-plate 45 is electrically connected with the conductor-plate 28 through the eyelet 46 and the screws 37. The screws 37 also serve to mechanically connect the insulating member 43 with the insulating member 18.

In wiring the device the insulating member 43 is detached from the insulating member 18, and the cord-extensions 48 are led up through the opening 49 in the insulating member 43 and secured beneath the heads of the binding-screws 47. The insulating member 43 is then secured to the insulating member 18 by threading the screws 37 into the conductor-plates 28.

In Figs. 8 to 12, inclusive, I have shown

a different type of wiring base and receptacle. The wiring base comprises an insulating member 50 and a pair of binding-terminals 51 supported thereby. The base 50 may be secured in proper position with respect to an electrical outlet by means of screws 52 extending through slots 53 in the insulating member 50. Each binding-terminal 51 comprises a screw 54 having its head located in a recess 55 in the lower face of the insulating member 50 and threaded into a conducting-plate 56 located in a recess in the upper face of the insulating member 50. The recess in which the conductor-plate 56 is located may be filled with a suitable insulating compound 57.

The receptacle portion comprises an insulating member 58, a center contact 59, and a cylindrical threaded-shell contact 60 supported by the insulating member 58. The center contact 59 is secured to the insulating member 58 by means of an eyelet 61 of metal. The center contact 59 is electrically connected with the conducting-plate 56 through the eyelet 61 and screw 62 which is threaded into the conducting-plate 56. The screw 62 also serves to mechanically connect the insulating member 58 with the insulating member 50.

The threaded shell contact 60 is electrically connected with one of the conducting-plates 56 by means of a screw 63 extending through an opening in the flange portion 64 of the threaded shell and threaded into the conducting-plate 56. This screw 63 also serves to hold the insulating member 58 in place with respect to the insulating member 50. The shank of the screw 63 between the head and the threaded portion is reduced so as to pass easily through the opening in the flange portion 64 of the threaded shell, but the threaded portion of the screw 63 is of such diameter that it must be threaded through the opening in the flange portion 64. By this construction the screw 63 is prevented from falling out of the threaded-shell contact 60 when it is unscrewed from the conducting-plate 56.

A friction washer 65 serves to prevent the screw 62 from dropping out of the eyelet 61 when the screw is screwed out of the conducting-plate 56.

The threaded-shell contact 60 is secured to the insulating member 58 by means of metal eyelets 66 (Fig. 11).

In wiring the device, the insulating member 58 is detached from the insulating member 50, the insulating member 50 is secured in proper position with respect to an electrical outlet by means of the screws 52 and the feed-wires are secured in place beneath the heads of the binding-screws 54. The insulating member 58 is then secured to the insulating member 50 by threading the screws 62 and 63 into the conducting-plates 56.

In order to grip a lamp-base or other device which is screwed into the threaded-shell contact 60, the contact 60 is provided with a pair of opposed slots 67 which follow the thread in the threaded-shell contact, and a wire spring 68 is mounted so as to have a portion extending through this slot into engagement with the lamp-base or other insertable device. The wire spring has one end 69 turned up, and the other end 70 turned down, and these ends 69 and 70 are located in grooves 71 in the insulating member 58.

The circuit is from one of the binding-screws 54, through the conductor-plate 56, screw 62, eyelet 61, center contact 59, translating device, shell contact 60, screw 63, and binding-plate 56 to the other binding-screw 54.

20 Either the quick-detachable receptacle 16 or the screw-shell receptacle shown in Fig. 8 may be used with the wiring base 15 of Fig. 1 or with the wiring base shown in Fig. 8. The screws 37 shown in Fig. 3 may be removed and the insulating base 31 separated from the insulating base 18, and the insulating base 58 of Fig. 8 may then be secured to the insulating base 18 by means of the screws 62 and 63. The screwing in of 25 the screws 62 and 63 makes the mechanical connection between the two insulating bases and also makes the electrical connection between the receptacle contacts and the binding-terminals.

30 This application is a continuation, so far as concerns common subject-matter claimed herein, of my pending application Serial No. 823,234, filed March 7, 1914, for an improvement in lamp sockets.

35 I claim as new and desire to secure by Letters Patent of the United States:

1. An electrical socket comprising a two-part insulating base, comprising upper and lower parts separable substantially on a plane transverse of the axis of the socket, 45 shell and center contacts mounted on the lower base part, wiring terminals for said contacts mounted on said base, the upper base part having an axial opening therethrough for the feed wires leading to said wiring terminals, said base parts having longitudinally extending registering openings therethrough, and means for securing said base parts together and electrically connecting one of said contacts with one of said wiring terminals, comprising a screw extending through said registering openings, and having its head accessible for operation from within said threaded shell contact. 50

2. An electrical socket comprising a two-part insulating base comprising upper and lower parts separable substantially on a plane transverse of the axis of the socket, shell and center contacts mounted on the lower base part, wiring terminals for said contacts mounted on said base, the upper base part having an axial opening therethrough for the feed wires leading to said wiring terminals, said base parts having longitudinally extending registering openings therethrough, and means for securing said base parts together, and electrically connecting said shell contact with one of said wiring terminals, comprising a screw extending through said registering openings, and having its head accessible for operation from within said threaded shell contact. 55

In witness whereof, I have hereunto subscribed my name.

REUBEN B. BENJAMIN.
